INVENTOR.

DAVID WILCOX, OF BOSTON, MASSACHUSETTS, ASSIGNOR TO HIMSELF, W. H. SLOCUM, AND W. A. BROWN, OF SAME PLACE.

Letters Patent No. 88,107, dated March 23, 1869.

IMPROVEMENT IN HATS.

The Schedule referred to in these Letters Patent and making part of the same.

To all whom it may concern:

Be it known that I, DAVID WILCOX, of Boston, in the county of Suffolk, and State of Massachusetts, have invented certain new and useful Improvements in the Manufacture of Hats; and I do hereby declare that the following is a full and exact description thereof, reference being had to the accompanying drawings, and to the letters of reference marked thereon.

To enable others skilled in the art to make and use my invention, I will proceed to describe its construction and use.

The nature of my invention consists in making the brim of the hat of twice the required width, and in applying the stiffening-preparation to one side of the same, after which the brim is doubled back upon itself, in such a manner that the stiffening-preparation shall be enclosed within the fold, as will be hereinafter more fully set forth.

In the drawings—

Figure 1 is a perspective view of the hat.

Figure 2 represents, in section, the same, the dotted lines *c c* representing that part of the brim that is folded back or under the brim *B B*, when the hat is complete.

I construct my hat as follows:

The felt body is made in the usual manner, except that the brim is of twice the desired width, as indicated by the dotted lines in fig. 2. The under side of this brim is coated with the stiffening-preparation, and is then doubled back upon itself, as indicated in fig. 2,

that is, the part *C*, is folded so as to occupy the position indicated by *C'*.

By this operation, the stiffening will be enclosed between the folds *C'* and *B* of the brim, and will serve as a cement to unite the parts thereof, and to stiffen the same.

The ordinary method of stiffening the brim, is to saturate it with the stiffening-preparation. This is very objectionable, as the preparation soon shows through the felt, and gives the brim a greasy and dirty appearance.

By my method, the stiffening is spread upon the surface of the felt, and then, the felt being folded, so as to bring the stiffening within the fold, there is no danger of the preparation working through and appearing on the exposed surface.

Having thus described my invention, I will proceed to set forth my claim.

What I claim as my invention, and desire to secure by Letters Patent of the United States, is—

A hat, whose brim is formed of twice the required size, and folded upon itself, the parts being united by the stiffening-material, or cement, applied to the inner surface of the folded parts, substantially as herein described, and for the purpose specified.

DAVID WILCOX.
